UNITED STATES PATENT OFFICE.

FREDERICK MARSTON, OF EL PASO, TEXAS.

BELT ELEVATOR AND CONVEYER.

1,194,308.

Specification of Letters Patent.

Patented Aug. 8, 1916.

Application filed April 8, 1914. Serial No. 830,413.

To all whom it may concern:

Be it known that I, FREDERICK MARSTON, a citizen of the United States, residing at El Paso, in the county of El Paso and State 5 of Texas, have invented a new and useful Improvement in Belt Elevators and Conveyers of which the following is a specification.

This invention relates to certain improvements in conveyers and has relation more particularly to a bucket conveyer wherein the belt is guided around crowned pulleys, and an object of the invention is to provide a device of this general character wherein 15 the inner surface of the belt is curved transversely in order to conform to the periphery of the pulleys in order to assure a maximum of frictional engagement.

The invention consists in the details of 20 construction and in the combination and arrangement of the several parts of my improved conveyer whereby certain important advantages are attained and the device is rendered simpler, less expensive and otherwise 25 more convenient and advantageous for use, all as will be hereinafter fully set forth.

The novel features of the invention will be carefully defined in the appended claims.

In order that my invention may be the 30 better understood, I will now proceed to describe the same with reference to the accompanying drawings, wherein—

Figure 1 is a view partly in elevation and partly in section, illustrating a general form 35 of conveyer coacting with the crowned pulley; Fig. 2 is a view partly in elevation and partly in section illustrating a conveyer constructed in accordance with an embodiment of my invention; and Fig. 3 is 40 a view partly in elevation and partly in section illustrating a modified form of my invention.

As disclosed in the accompanying drawings, 1 denotes a belt adapted to pass around 45 the crowned pulley 2, and 3 denotes a bucket secured to the outer surface of the belt through the medium of the conventional bolts 4 and their coacting nuts 5, the heads of the bolts being disposed inwardly of the 50 belt and flush with the inner face thereof while the nuts 5 are positioned within the bucket 3. The bolts 4 are arranged preferably at the transverse center of the inner face 6 of the bucket and adjacent the opposite ends thereof, whereby the portion of the belt immediately behind the bucket is ar-

ranged substantially rigid and non-yielding and of a uniformity in shape.

As particularly disclosed in Fig. 2, the inner face 6 of the bucket 3 is curved transversely concentric to the transverse curvature of the pulley 2, whereby it will be perceived that a similar curvature will be imparted to the belt 1, whereby it is assured that an engagement possessing a maximum 65 of efficiency may be had between the pulley 2 and the belt 1.

As illustrated in Fig. 3, the bucket 3' and belt 1' have interposed therebetween a liner plate 7, the outer face 8 whereof being 70 curved transversely concentric to the curvature of the crowned pulley 2', while the bolts 4' together with the coacting nuts 5' serve to maintain the belt 1', liner 7 and bucket 3' in operative engagement. It will 75 also be observed that the outer face of the liner plate 7 serves to give the belt 1 the requisite transverse curvature to properly engage the periphery of the crowned pulley 2'. 80

The advantages of my invention as illustrated in Figs. 2 and 3 of the accompanying drawings are thought to be made apparent by the disclosure contained in Fig. 1 wherein a conventional bucket conveyer is employed wherein it will be observed that the rear face of the bucket B is straight, which results in the engagement of the belt A with the pulley P with the minimum of efficiency. 85

From the foregoing description it is 90 thought to be obvious that a conveyer constructed in accordance with my invention is of an extremely simple and comparatively inexpensive nature, and is particularly well adapted for use by reason of the convenience 95 and facility with which it may be assembled and by reason of the effectiveness with which it performs its functions, and it will also be obvious that my invention is susceptible of some change and modification without material departure from the principles and spirit thereof and for this reason I do not wish to be understood as limiting myself to the precise arrangement and formation of the several parts herein shown of 100 my invention in practice.

I claim:

1. In combination with a crowned wheel, a belt adapted to be disposed therearound, a bucket secured to the belt, the contacting 110 face of the bucket being disposed on a curve concentric to the transverse curvature of the

periphery of the crowned wheel whereby the belt is disposed on a corresponding transverse curvature and means for rigidly connecting the contacting face of the bucket and the adjacent portion of the belt.

2. In combination with a crowned wheel, a belt adapted to be disposed therearound, a bucket having its back face secured to the belt, said back face of the bucket being caved to conform to the transverse curvature of the periphery of the crowned wheel, bolts disposed through the back face of the

bucket and the adjacent portion of the belt, said bolts being positioned at substantially the transverse center of the back and adjacent opposite margins thereof, the heads of the bolts being arranged inwardly of the belt and flush with the inner face thereof, and clamping nuts engaged with the extremities of the bolts within the bucket.

15 FREDERICK MARSTON.
